UNITED STATES PATENT OFFICE.

HUGH ALEXANDER GRIFFIN, OF LINDSAY, CALIFORNIA.

FURNACE FOR STEAM BOILERS FOR BURNING RESIDUAL MOLASSES.

Application filed December 6, 1921. Serial No. 520,379.

To all whom it may concern:

Be it known that I, HUGH ALEXANDER GRIFFIN, a citizen of the United States, and a resident of Lindsay, in the county of 5 Tulare and State of California, have invented certain new and useful Improvements in Furnaces for Steam Boilers for Burning Residual Molasses, of which the following is a specification.

10 My present invention relates generally to steam boilers, and more particularly to a steam generating apparatus which will burn and thus utilize for steam generating purposes residual molasses and like products 15 of waste fluid, my object being the provision of a simple effective apparatus capable of ready extension in its adaptability to steam boilers of varying widths, and applicable in a ready simple manner to boilers of 20 various types.

In the present instance I have shown my invention as applied to a fire tube boiler of the horizontal tubular type and have illustrated means, constituting the invention, 25 whose purpose is to uniformly feed the molasses in such manner as to promote combustion of maximum efficiency.

In the accompanying drawings illustrating my invention and forming a part of 30 this specification,

Figure 1 is a vertical longitudinal section through a steam boiler such as I propose taken on line 1—1 of Figure 2.

Figure 2 is a vertical transverse section 35 taken on line 2—2 of Figure 1, and

Figure 3 is a front elevation, partly in section, looking from the line 3—3 of Figure 1.

Referring now to these figures it will be 40 noted that the boiler 10 is arranged longitudinally in my improved molasses burning furnace above a hollow arch or bridge wall 11 and between the rear portion of the latter and the rear furnace wall 12 a passage- 45 way 13 is left for the products of combustion of the fire box 14 so that these products can enter the rear ends of the fire tubes 15. The forward ends of the fire tubes 15 discharge into a header 16 from the lower portion 50 of which an ash discharge pipe 17

leads, ash arresting means being employed in the header above the level of the boiler and consisting of a fluid discharge pipe 18 which discharges a sheet or film of water 19 across the header above the discharge ends 55 of the fire tubes, the water serving to arrest the ash and also to wash the same steadily to any suitable point of discharge through the ash discharge pipe 17.

Within the lower portion of the fire box 60 14 is a grate 20 preferably of the horizontal sliding type, disposed on grate supports 21, and actuated by a connecting rod 22 from an external shaking lever 23. This grate 65 may be in two sections, each with its shaking lever 23 and each with its connecting rod 22, the latter of which may lead into the fire box through slotted openings 24 in the fire box doors 25, the latter of which 70 may have the usual, or in fact any suitable draft arrangements.

Into the side walls 26 of the furnace, opposite the upper portion of the fire box, and below the arch or crown wall 11 are set bearing supporting plates and the like 27, 75 each having one or more bearing brackets 28 for hollow transverse shafts 29, whose portions, between the bearing brackets 28, are preferably squared as seen particularly in Figure 1 to receive thereon one or more 80 cylinders 30 whose function is to support cylindrical drip catchers 31 disposed in end-wise abutting relation and in any suitable number on the cylinders. Each of these cylindrical drip catching plates has flanged 85 ends 32 and is circumferentially divided by lengthwise ribs and the like into a plurality of drip catching receptacles, which in the rotation of the cylinders with the drip catching plates thereon, receive molasses 90 from transverse series of drip apertures 34 of the arch or crown wall 11, arranged therein along and above the axes of the cylinders.

For the supply of molasses, a molasses 95 supply pipe 35 extends into the hollow of the crown wall or arch 11 and has diverging and downwardly inclined branch delivery pipes 36 whose lower curved ends enter the upper enlarged portions 37 of the 100

drip apertures 34 so that from the single pipe 35, the drip or feed plates 31 of both cylinders may be supplied.

The drip or feed plates 31 may be keyed 5 or otherwise secured upon the supporting cylinders 30, and the hollow shafts 29 are extended laterally beyond one side of the furnace to a sufficient distance adapting them to receive interengaging spur gears 38 10 and also adapting one of the shafts, as seen in Figure 2 to receive a worm wheel 39 engaged by the worm 40 of a shaft 41 mounted in brackets 42 at one side of the furnace and driven from any suitable source of power 15 as for instance through a belt 43 and pulley 44.

Thus in action it is obvious that the two supporting cylinders 30 will be rotated in opposite directions and that due to this manner 20 and means of feeding the molasses, the latter passes inwardly through the molasses supply pipe 35 and dripping from the branches 36 of this pipe, will be broken up and carried around the cylinders by the 25 drip or feed plates 31 in shallow pools and thus gradually heated to a point of ready combustion upon the final discharge of these shallow pools onto the fire on the grate 20.

In this way the molasses is freed from 30 most of its dilution water by the heat of the fire before it reaches the flame and in this way is rendered much more efficient as a fuel for it is in condition for instant combustion when the flame is reached and is 35 thus in condition to generate greater heat in the furnace.

The hollow shafts 29 on which the cylinders are mounted, are in practice continuously supplied with water as a cooling 40 fluid, which enters one end of each shaft and discharges from the other end and which in its passage through the shaft cools the bearings thereof and maintains the parts in condition for effective operation.

45 Thus by the improved apparatus I propose, the molasses may be fed to the furnace in the first instance by gravity alone in the form of drip during the course of which as well as the uniform feed of the molasses, its dilution water is evaporated for the above stated purposes.

Furthermore by this apparatus I am enabled to provide for the effective utilization 55 of otherwise wasted products of sugar factories and the like and I not only permit of the utilization of these otherwise wasted products for effective purposes, but in such a way that the ash, having a high fertilizing value, can be readily recovered, for instance 60 by means of the ash arresting means described in the header 16 which has a further advantage that it will leave banking of ash near the boiler.

I claim:

65 1. A molasses burning steam boiler fur-

nace having a fire box, a grate in the lower portion of the fire box, a crown wall over the fire box whose rear portion is spaced from the rear wall of the furnace to form a passageway for the products of combustion 70 of the fire box, a boiler above the crown wall having fire tubes whose rear ends are open to the said passageway, a header into which the forward ends of the tubes open, means for arresting ash within and discharging 75 the same from said header, said crown wall having apertures in a line above the grate, pipes for feeding molasses by gravity through said apertures, and means within the upper portion of the fire box to retard 80 the flow of molasses downwardly to the grate and within the fire box subject to the heat thereof.

2. A molasses burning steam boiler furnace having a fire box, a grate in the lower portion of the fire box, a crown wall over the fire box whose rear portion is spaced from the rear wall of the furnace to form a passageway for the products of combustion 85 of the fire box, a boiler above the crown wall having fire tubes whose rear ends are open to the said passageway, a header into which the forward ends of the tubes open, means for arresting ash within and discharging 90 the same from said header, said crown wall having apertures in a line above the grate, pipes for feeding molasses by gravity through said apertures, and means within the upper portion of the fire box to retard the flow of molasses downwardly to the grate and within 95 the fire box subject to the heat thereof, said last named means including a rotating cylinder having peripheral pockets to receive the molasses from said apertures, and means externally of the furnace for rotating 100 said cylinder as and for the purpose described.

3. In a molasses burning furnace having a fire box, a hollow crown wall or arch over the fire box provided with vertical apertures 110 in a line, gravity connections feeding molasses into said apertures, and a rotatable cylinder below the apertures having peripheral pockets to receive the drip from the apertures, and a grate in the fire box below 115 the cylinder.

4. In a molasses burning furnace having a fire box, molasses feeding means including rotatable cylinders in the upper portion of the fire box having peripheral pockets in 120 which the molasses is exposed to the action of the heat of the fire box before it is finally dropped into the fire.

5. In a molasses burning furnace having a fire box, molasses feeding means including 125 horizontally disposed cylinders rotatable in the upper portion of the fire box, having peripheral pockets which deliver molasses to the fire at the lower portions of the cylinders, and means for feeding molasses by 130

gravity to the upper portions of the cylinders.

6. In a molasses burning furnace having a fire box, molasses feeding means including gravity feed pipes leading to the upper portion of the fire box, and means to receive molasses from the said pipes, acting to re-

tard the flow of molasses to the flame within the influence of the heat of the fire box, said last named means including rotating cylinders having peripheral pockets into which molasses drips from the said feed pipes. 10

HUGH ALEXANDER GRIFFIN.
